UNITED STATES PATENT OFFICE.

ELIZEBETH GROSS, OF PHILADELPHIA, PENNSYLVANIA.

DESIGN FOR A BASE FOR BEER-COOLERS.

SPECIFICATION forming part of Design No. 34,755, dated July 9, 1901.

Application filed April 13, 1901. Serial No. 55,792. Term of patent 14 years.

To all whom it may concern:

Be it known that I, ELIZEBETH GROSS, a citizen of the United States, residing at the city of Philadelphia, in the county of Philadelphia and State of Pennsylvania, have invented a certain new and useful Design for a Beer-Cooler Base or Partition, of which the following is a specification, reference being had to the accompanying drawings, forming part hereof.

Figure 1 is a top perspective view of the base of a beer-cooler, showing my design; and Fig. 2 is a bottom perspective view of the same.

As shown in the drawings, the leading or material feature of my design consists of the curved walls 1 and ribs 2, disposed or arranged as shown in Fig. 1, which together form a sinuous channel, as shown. The ribs

3 project from the under side of the base, and 20 the parts 4 project from the edge thereof.

As shown, the exterior of the base at its edges conforms to the sinuous turnings of the channel.

The shape of the base as a whole is that of 25 a very wide and shallow receptacle having exceedingly thin walls.

What I claim as new, and desire to secure by Letters Patent, is—

The design for the base of a beer-cooler as 30 herein shown and described.

In testimony whereof I have hereunto signed my name.

ELIZEBETH GROSS.

In presence of—

W. J. JACKSON,
FRANK T. KALAS.
